MULTISYSTEM TUBE

Bruno Wienecke, Berlin, Germany

Application February 5, 1934, Serial No. 709,705
In Germany February 6, 1933

4 Claims. (Cl. 250—27.5)

The subject matter of the present invention is a novel arrangement of the electrode systems in multi-system tubes for mounting the systems to be free of vibration, and a method of obtaining a rigid assembly of the systems. The arrangement and the method are for use both in connection with rectifier tubes, and more particularly two-way rectifier tubes, as well as for power amplifier tubes and transmission tubes, insofar as these possess a plurality of systems.

It has been found that without the arrangement of the systems according to the invention a displacement of the systems or the single parts thereof frequently takes place by the vibration of these tubes of relatively high output. Owing to this relative displacement of the systems or system parts the tube data is naturally a different one, and the tubes are thus made incapable of use.

It has also been found that in the production of tubes of relatively high output as hitherto known the most frequent error in manufacture consists in rupture or fracture of the pinch. This is due to the fact that the electrodes, and more particularly the anodes, are secured in direct fashion to the leading or holding rods fused into the glass pinch. In the heating of the metallic parts necessary for outgassing purposes there occurs, however, a strong conduction of heat over these short holding rods to the glass pinch, so that inadmissible thermal stresses are produced, which may lead to rupture of the pinch. It may also occur on occasion that, owing to overloading during operations, more particularly the anodes become excessively heated, and that also in this case the glass pinch may become fractured owing to conduction of the heat.

According now to the invention, the electrode systems are first united to form a firm self-contained mechanical structure. This is performed in such fashion that the single electrode systems are so supported in relation to each other by means of diagonal braces that the systems have no possibility whatsoever of moving in relation to each other. The diagonal braces are produced from a highly insulating material, which may be readily outgassed, for example mica, and are connected together at the point of intersection. The diagonal braces, however, may also be produced in one piece, which conveniently is in the form of an X. To these there are secured in accordance with the invention cross bars for holding the electrodes, for example the anodes, which bars are mounted firmly in corresponding borings in the diagonal braces. To avoid con-

tact between the anodes and the strips of mica, which might lead to disturbances, particularly when the system is loaded, by heating the anodes, small spacers are provided, for example of ceramic material, which upon the assembly of the total system structure are slipped over the cross bars secured to the anodes.

The assembly of the total system on the pinch in accordance with the invention is now performed in such fashion that the total system rests upon the pinch merely by means of the mica braces in two-point or two-surface contact, possibly with rectangular or trapezoidal cross-section. The diagonal braces are provided at a suitable point, preferably at the centre, with a small metal plate, which may conveniently be secured to said braces by riveting. Said metal plates are secured, preferably by spot welding, to short holding rods, which are fused into the pinch and secure in this way the entire system in its position on said pinch.

The filaments which may preferably be V-shaped are held by means of resilient leads connected to each of the ends of the filament. The centre-point of the filament is held firmly on a cross strut between the diagonal braces. To support the current leads for the cathode there is provided in accordance with the invention a transverse bracing, preferably composed of mica, between the diagonal braces on either side, which transverse bracing ensures a sufficient spacing between the current leads. By reason of the arrangement according to the invention it is accomplished that insofar as the electrodes of a certain system possess a certain freedom of movement at all in relation to each other, these electrodes, for example the cathodes of the system, are unable to move in the direction from anode to cathode, but only in a direction vertical thereto. This is particularly important in the case of rectifier systems, in which the spacing between cathode and anode is extremely small.

The assembly of the systems according to the invention is illustrated in the drawing in conjunction with a possible form of embodiment of a two-way rectifier.

Fig. 1 is a complete view of the system according to the invention, while in Fig. 2 there is shown an elevation and in Fig. 3 a plan of the system with the same reference characters as in Fig. 1.

In Fig. 1, 1 is the glass pinch having the pump tube 2 attached thereto, 3 and 4 the box-shaped anodes, and 5 and 6 the cathodes guided in the form of a V. In the pinch there are fused the

holding rods 7 and 8, which at the same time are constructed to form leads for the anodes. Over these holding rods there is slipped and secured the structure carrying the systems. The 5 anode systems are connected with each other by means of the cross-members 9 and 10. This connection causes on the one hand the combination of the electrode systems to form a mechanical unit, and on the other hand, insofar 10 as relative displacement of the electrodes is still possible at all, provides security against the danger of short-circuiting and other electrical disadvantages. 9 and 10 are the diagonal braces according to the invention, which consist of a 15 highly insulating material readily capable of being outgassed, for example of mica, and are in the form of an X. They are bored at the ends, and carry the anodes by means of transverse bars 22 and 23 secured thereto, spacers 28, composed 20 for example of ceramic material, being provided to avoid contact between the anodes and the pieces of mica. There are also fused into the pinch a middle holding rod 11 and the leads 13 and 14 for the cathodes 5 and 6. The spacing 25 between these electrodes is ensured by means of a cross strut 15. The fixed holding of the filaments at the bottom is performed by means of the transverse rod 21 with the abutment 26, whilst the upper lead is constructed to be elastic 30 by means of the resilient yokes 24 or 25 for each filament. The pieces of mica 9 and 10 carry at the centre a circular metallic disc 16, which is riveted firmly to the mica itself. By means of the bent abutments 17 and 18 furnished with 35 apertures the rigid system structure is slipped over the holding rods 7 and 8 until it rests firmly at two points or surfaces against the pinch at 12, and is then welded to the rods 7 or 8 with the assistance of the plate 19. At the same time 40 there are also welded to this plate 19 a suitable getter material 20, for example, magnesium, and the anode lead 27.

It is also possible, in addition to the electrode systems assembled in accordance with the invention, to fit coupling elements in the same vacuum space, or to provide any additional electrode systems, which are not assembled in the manner according to the invention.

The particular and essential features of the 50 present invention are to be regarded in the fact that

(1) The bracing of the systems or system parts in relation to each other is performed by means of diagonal braces,

55 (2) The centre of gravity of the total system structure is disposed as low as possible, preferably below the supporting points for the system on the pinch,

(3) The diagonal braces may each be produced 60 from a strong and preferably X-shaped piece of material,

(4) The total system is mounted by (two-point or two-surface) bearing of the diagonal braces against the pinch, and additional holding 65 is performed by securing the total system to holding rods, preferably by means of spot welding,

(5) The arrangement is such that no heat-conductive connection exists between the anodes

and the pinch, and a heat insulation is provided between the anodes and the pieces of mica,

(6) The cathodes, which are preferably guided in the form of a V, are secured on the one side to a transverse strut, which is mounted on the diagonal braces, and at the two other ends are secured resiliently in respect of each filament section to avoid any irregular or insufficient tension of these filament sections.

I claim:

1. In an electron discharge device a stem having a press portion, two cathodes, two box-shaped anodes, two diagonal braces consisting of a highly insulating and highly vacuum-proof material, the ends of said braces connected with each other by four transverse rods and with said anodes forming a mechanical unit without heat-conductive connections, said unit being rested upon said press portion in two-point contact by means of said diagonal braces, the centre of gravity of said unit situated below the upper surface of said press portion.

2. In an electron discharge device a stem having a press portion, two cathodes, two box-shaped anodes, two diagonal braces consisting of a highly insulating and highly vacuum-proof material, the ends of said braces connected with each other by four transverse rods and with said anodes forming a mechanical unit without heat-conductive connections, said unit being rested upon said press portion in two-point contact by means of said diagonal braces, the centre of gravity of said unit situated below the upper surface of said press portion, said diagonal braces secured against displacement by additional holding means comprising holding rods fused in the press portion and connected with metallic discs fixed in the centre of said diagonal braces.

3. In an electron discharge device a stem having a press portion, two cathodes, two box-shaped anodes, two diagonal braces consisting of a highly insulating and highly vacuum-proof material, the ends of said braces connected with each other by four transverse rods and with said anodes forming a mechanical unit without heat-conductive connections, said unit being rested upon said press portion in two-point contact by means of said diagonal braces, the centre of gravity of said unit situated below the upper surface of said press portion, a heat insulation comprising spaces of ceramic material provided between said anodes and said diagonal braces.

4. In an electron discharge device a stem having a press portion, two cathodes, two box-shaped anodes, two diagonal braces consisting of a highly insulating and highly vacuum-proof material, the ends of said braces connected with each other by four transverse rods and with said anodes forming a mechanical unit without heat-conductive connections, said unit being rested upon said press portion in two-point contact by means of said diagonal braces, the centre of gravity of said unit situated below the upper surface of said press portion, the lower end of said cathodes secured firmly on a transverse strut mounted on said diagonal braces, the upper ends of said cathodes being held in resilient fashion, cathode leads supported by a transverse bracing mounted in said diagonal braces.

BRUNO WIENECKE.
